UNITED STATES PATENT OFFICE

2,175,172

BLEACHING AND TREATING OF FLOUR AND
AGENT THEREFOR

Souren Z. Avedikian, New York, N. Y.

No Drawing. Application July 3, 1936,
Serial No. 88,837

21 Claims. (Cl. 99—232)

It is known that nitrogen oxides and certain compounds capable of liberating nitrogen oxides in contact with flour have been proposed as bleaches for flour. Nitrogen peroxide, NO_2 , in the gaseous form has been used successfully in the past. As examples of known compounds capable of liberating nitrogen oxides in contact with flour, nitrosyl chloride, a gas, and nitrosyl sulfuric acid, a solid at ordinary temperatures, 10 may be mentioned. In contact with flour, they presumably react with the moisture present therein to give oxides of nitrogen and hydrochloric acid in the first case, and sulfuric acid in the second.

15 It is recognized to be desirable from the viewpoint of the miller that the bleaching substance be in such a state that it can be used readily without hazard. The gaseous agents mentioned above involve danger to health, product and 20 equipment unless proper precautionary measures are adopted in their use. Carelessness on the part of the operator may have serious results.

Those compounds which contain nitrogen oxides bound within their molecules, especially 25 those in the solid state, and which can be made to liberate it when in contact with moisture, have decreased the hazards inherent in the use 30 of nitrogen oxides, and have supplied the miller with a relatively easily applicable bleaching compound, possessing the peculiarly beneficial effects 35 of nitrogen oxides on flour. However, all these substances that have been mentioned for or used as bleaches have one characteristic in common. That is, they all impart to flour an excess of one 40 equivalent of acidity or more for each mole of oxide of nitrogen that is effective in the bleaching operation. Now, it is well known that excess acidity is undesirable in flour and that the pH 45 of flour must be maintained within certain definite limits in order to obtain optimum results in maturing and aging and in subsequent use in bread-making. Consequently, manufacturers 50 of this type of bleach have adopted the expedient of mixing with their bleaching substances basic materials to rectify too high an acid condition and to obtain eventually, as nearly as possible, 55 the proper acidity.

The question of whether these alkaline substances are effective in neutralizing, in situ, the 55 acidity produced may be debatable, but the danger exists that in the relatively dry, powdery state of flour, local acid or alkaline spots or both will develop and will persist until the flour is made into dough. It is recognized that storage of flour under an excessively acid or alkaline con-

dition is harmful. Hence, in the use of these types of bleaches, there exists a period in the life of the flour during which the pH is likely to be either too low or too high in certain places.

A second disadvantage is that the substances 5 capable of liberating nitrogen oxides, heretofore known and used as bleaches for flour, are extremely sensitive to moisture. They deteriorate readily in storage and very rapidly upon exposure to traces of moisture. Great care must be exercised in their handling, otherwise their value in use is lost. This militates against their extensive commercial application.

A great many other substances have at various 15 times been used as bleaches. Organic peroxides are among these now most in favor, and they are used in the form of a diluted dry powder. The miller adds a small percentage of it to his flour and after about a day or two obtains the desired 20 bleaching effect. This ease of application has 25 made it attractive to the miller. Their manufacture, however, is attended with fire and explosion hazards; furthermore, the known methods of preparation are troublesome and costly. As a result, the bleaching compound is sold to the 30 millers at a high price.

Now I have found a new and useful treating agent for flour and other milling products and have thus provided a new process suitable for the bleaching and improving of these food materials. My bleaching agent is an addition compound of sodium nitrite (or its equivalent) and sulfur trioxide, which upon mixing with flour 35 exerts a powerful bleaching effect upon it. It seems probable that this flour bleach acts by 40 liberating nitrogen oxides through decomposition by the water or moisture of the flour.

The agent which I employ is a chemically different type of compound from formerly-known 45 flour bleaches capable of yielding nitrogen oxides, and possesses special advantages and distinctly 50 superior qualities. Notwithstanding that it is an extremely active flour bleach, it is remarkably 55 more stable in storage than the others, and preserves its strength for a much longer time; nor does it attack the storage container.

Furthermore, it is very easily prepared, by a 55 process which I have devised and will describe, from relatively inexpensive starting materials, namely, sodium nitrite and sulfur trioxide. The 60 product of the reaction between these materials is a solid and can be ground to a fine powder. It is non-toxic in use, acts on the color in the flour or the milling product, is highly effective in whitening, and produces improvement in the 65

quality of the flour. In bleaching by this method, the substances added are natural to flour. The residue of decomposition of this addition compound is neutral sodium sulfate, which does not appreciably affect the pH of the flour.

I have found that this flour bleaching agent can be successfully prepared by directly bringing together the ingredients, with agitation, and that the sulfur trioxide may be thus utilized in either the liquid or the gaseous state.

It appears that when sodium nitrite, or its equivalent, and sulfur trioxide are brought together a combination or union takes place between them as follows:

where n may have any value from a small fraction to 3.

The compound formed appears to be of the same general type of complex compounds to which certain ammonia complexes belong, e. g., $\text{Cu}(\text{NH}_3)_4^{++}$, $\text{Ag}(\text{NH}_3)_2^{++}$, $\text{Ni}(\text{NH}_3)_x^{++}$, etc., in which the metallic ion behaves as if there were a number of ammonia molecules attached to it. In the present case, the addition compound behaves as if there were either a number of sulfur trioxide molecules attached to the sodium nitrite molecule or a number of sodium nitrite molecules attached to the sulfur trioxide molecule. I find that by my process of preparation I can put into the addition compound any quantity of sulfur trioxide less than three molecules. Thus, this compound can be made in various gradations by my process, such that sulfur trioxide varies from one mole per two moles of sodium nitrite to one to one, etc. The former I have found to be preferred as a bleach for flour.

According to one form of my process for preparing a flour bleaching agent, I may take 80 grams of sulfur trioxide in the liquid state and add to it slowly, with agitation, 69 to 138 grams of sodium nitrite, preferably well ground. Or, I may add the liquid sulfur trioxide slowly to the solid sodium nitrite first placed into the reaction chamber. The reaction producing the addition compound is highly exothermic. Therefore, I prefer to keep the reaction chamber and its contents relatively cool by surrounding the vessel with cold water or a stream of liquid to dissipate the heat. I find that temperature of the surrounding medium between 15° and 40° C. at ordinary pressures are satisfactory, but other temperatures and pressures may be used. The formation of this compound is rapid and the reaction reaches completion in a relatively short time. I prefer, however, to let the reaction mixture stand for a few hours before further treatment. After about 3-4 hours or more, as the case may be, I remove the contents of the vessel, break up the coarse aggregates that may have formed, and, preferably after admixture with a water absorbing (or adsorbing) material, such as active clay, anhydrous sodium sulfate, anhydrous calcium sulfate, colloidal silica, silica gel, etc., I grind it to a fine powder. This fine powder acts as an effective bleach and improver for flour. The color of flour is lightened considerably and the resulting bread has a lighter appearance and the loaf is larger in volume than ordinarily.

As an alternative procedure, place 69 to 138 grams of sodium nitrite in a reaction chamber which is equipped to maintain the solid substance in a state of constant agitation, either by tumbling as in a ball mill or a tumbling mixer,

or by means of a rotating agitator within a stationary shell. The chamber should preferably be designed to dissipate the heat of the reaction quickly and effectively as by a cooling-water jacket, etc. Then, after the agitation has been started, lead into the chamber a stream of sulfur trioxide in the gaseous state, either pure undiluted sulfur trioxide or this gas diluted with an inert gas such as air, nitrogen, carbon dioxide, etc. The term "inert" is used here in the sense that the diluting gas does not itself take part in the reaction but is instrumental merely in supplying sulfur trioxide in smaller quantities than would otherwise be possible, in the event that a slower and a better controlled reaction with sodium nitrite is desired. When the required amount of sulfur trioxide has been passed into the reaction chamber, i. e., to produce a compound from 1:1 to 2:1 in ratio with respect to sodium nitrite and sulfur trioxide as desired, discontinue the stream of sulfur trioxide and allow the mixture to stand for a few hours and then grind it to a fine powder in the presence of a water absorbent material such as anhydrous sodium sulfate, silica gel, etc., singly or in combinations of two or more.

The following are specific examples:

Example I

	Parts
Sulfur trioxide	80 30
Sodium nitrite	69
Sodium sulfate (anhydrous)	16

To the sulfur trioxide in the liquid state is added, slowly with stirring, in a cooled vessel the sodium nitrite. The agitation and cooling are continued until the reactivity of the mixture ceases. The mixture is now allowed to stand a few hours in the cooling bath, after which it will be ready to grind and pulverize. After breaking up coarse aggregates, the anhydrous sodium sulfate is admixed and the whole is ground to a fine powder in a suitable mill, e. g. a ball mill.

Example II

	Parts
Sulfur trioxide	80
Sodium nitrite	138
Sodium sulfate (anhydrous)	24

The reaction and the subsequent operations may be carried out as described under Example I.

The quantities and substances above mentioned are in accordance with the preferred embodiment of that part of my invention which involves the preparation of the addition compound, which I have discovered to be valuable as a flour bleach. I have found, however, that variations within the quantities above specified and also outside those quantities are possible for the production of a dry powdery substance capable of bleaching flour. The ratio of sodium nitrite to sulfur trioxide may vary from 1:2 or less to 2:1 and even higher, for example 4:1, with a resulting product which upon reacting with water or moisture liberates nitrogen oxides. The liberation of oxides of nitrogen, however, does not appear to be complete when the ratio is greater than 2:1. On the other hand, the bleaching effect of the compound on flour and the like would be considerably diminished if the ratio should closely approach 1:3. All such variations are intended to be within the scope of this invention.

The foregoing description and the examples given above have mentioned sodium nitrite. This

has been done merely for the sake of clarity in the exposition and with no intention of limiting myself to the use of sodium nitrite solely. The nitrites of lithium, potassium, and calcium, i. e., 5 those which are capable of forming an addition compound with sulfur trioxide analogous to that of sodium nitrite, are equivalents of sodium nitrite for the purpose of my invention.

The process of bleaching flour or other milling 10 product with the herein described material is to mix a small amount of the bleach with the milling product, after which the thus-treated flour is allowed to stand. Suitable proportions are 1 part of the mixture of Example I, finely ground, 15 with 7,000 parts of flour. The resulting flour has a most desirable quality of whiteness. It also has a greater water absorption value than ordinary flour and the bread produced therefrom is of a finer texture than that which would be produced from the untreated flour.

Having thus broadly outlined my invention, and having specifically mentioned the substances that I use in the preferred embodiment of my invention, and method of application thereof, I claim 25 the following:

1. The process of treating flour and other milling products to bleach the same, which comprises mixing therewith an addition compound of sulfur trioxide and the nitrite of a metal of the group 30 consisting of lithium, sodium, potassium, and calcium.

2. The process of treating flour and other milling products to bleach the same, which comprises mixing therewith an addition compound of sulfur 35 trioxide and sodium nitrite.

3. The process of treating flour and other milling products to bleach the same, which comprises mixing therewith an addition compound of sulfur trioxide and the nitrite of a metal of the group 40 consisting of lithium, sodium, potassium, and calcium, utilizing as such bleaching agent a compound in which there are less than 3 molecular parts of sulfur trioxide to 1 part of the nitrite.

4. The process of treating flour and other milling products to bleach the same, which comprises mixing therewith an addition compound of sulfur trioxide and the nitrite of a metal of the group consisting of lithium, sodium, potassium, and calcium, utilizing as such bleaching agent a compound 50 in which the ratio of the nitrite to sulfur trioxide is between substantially 1:2 and 2:1.

5. The process of treating flour and other milling products to bleach the same, which comprises mixing therewith an addition compound of sulfur 55 trioxide and the nitrite of a metal of the group consisting of lithium, sodium, potassium, and calcium, utilizing as such bleaching agent a compound in which the ratio of the nitrite to sulfur trioxide is approximately 2:1.

6. The process of treating flour and other milling products to bleach the same, which comprises mixing therewith an addition compound of sulfur trioxide and sodium nitrite, in which compound the ratio of sodium nitrite to sulfur trioxide is 60 approximately 2:1.

7. A bleaching agent for flour and milling products, comprising a complex addition compound formed by the reaction of sulfur trioxide with the nitrite of a metal of the group consisting of lithium, sodium, potassium and calcium, in which 70 there is less than 3 molecular parts of the trioxide to 1 part of the nitrite and more than 1 of sulfur trioxide to 4 parts of the nitrite, which upon admixture with flour and milling products produces 75 a lightening of the color thereof.

8. A bleaching agent for flour and milling products, comprising the addition compound of sulfur trioxide and the nitrite of a metal of the group consisting of lithium, sodium, potassium and calcium formed by the reaction between the trioxide and the nitrite, wherein the ratio of the nitrite to sulfur trioxide is between substantially 1:2 and 2:1, which upon admixture with flour causes a lightening of the color thereof.

9. The process of treating flour and milling 10 products to bleach the same, which comprises adding thereto and mixing therewith a compound having the formula $R(SO_3)_xNO_2$, wherein R represents a metal of the group consisting of sodium, lithium, potassium and calcium, and x is less than 15 3.

10. The process of treating flour and milling products to bleach the same, which comprises mixing therewith a compound having the formula $Na(SO_3)_xNO_2$, wherein x is less than 2.

11. A bleaching agent for flour and milling products having the formula $R(SO_3)_xNO_2$, wherein R represents a metal of the group consisting of sodium, lithium, potassium and calcium.

12. The process of treating flour and milling 25 products to bleach the same, which comprises adding thereto and mixing therewith a compound having the formula $(R)_x(SO_3)(NO_2)_x$, wherein R represents a metal of the group consisting of sodium, lithium, potassium, and calcium, and x equals 30 2 to 4.

13. The process of treating flour and milling products to bleach the same, which comprises adding thereto and mixing therewith a compound having the formula $(Na)_2(SO_3)(NO_2)_2$.

14. A bleaching and maturing agent for flour and milling products having the formula $(Na)_2(SO_3)(NO_2)_2$.

15. The process of treating flour and other milling products which comprises mixing therewith an addition compound of sulfur trioxide and the nitrite of a metal of the group consisting of lithium, sodium, potassium, and calcium, to produce a maturing effect thereon with resulting improvement in baking quality, loaf volume, 45 water absorption, and texture of bread baked therewith.

16. The process of treating flour and other milling products which comprises mixing therewith an addition compound of sulfur trioxide and sodium nitrite, to produce a maturing effect 50 thereon.

17. The process of treating flour and other milling products which comprises mixing therewith an addition compound of sulfur trioxide and sodium nitrite, in which compound the ratio of sodium nitrite to sulfur trioxide is between substantially 1:2 and 2:1, to effect maturing thereof.

18. The process of treating flour and other milling products, which comprises mixing therewith an addition compound of sulfur trioxide and sodium nitrite, in which compound the molecular ratio of sodium nitrite to sulfur trioxide is approximately 2:1, to effect maturing thereof.

19. A maturing agent for flour and milling 65 products, comprising a complex addition compound formed by the reaction of sulfur trioxide with the nitrite of a metal of the group consisting of lithium, sodium, potassium and calcium, in which there is less than 3 molecular parts of the trioxide to 1 part of the nitrite and more than 1 part of sulfur trioxide to 4 parts of the nitrite, which upon admixture with flour and milling products produces a maturing effect thereon.

20. A maturing agent for flour and milling

products, comprising the addition compound of sulfur trioxide and the nitrite of a metal of the group consisting of lithium, sodium, potassium and calcium formed by the reaction between the 5 trioxide and the nitrite, wherein the ratio of the nitrite to sulfur trioxide is between substantially 1:2 and 2:1, which upon admixture with flour and

milling products produces a maturing effect thereon.

21. A maturing agent for flour and milling products, having the formula $R(SO_3)NO_2$, wherein R represents a metal of the group con- 5 sisting of sodium, lithium, potassium and calcium.

SOUREN Z. AVEDIKIAN.
